Attorney

UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

WORK DRIVER.

Application filed January 28, 1920. Serial No. 354,755.

To all whom it may concern:

Be it known that I, FRIEDERICH MÜLLER, a citizen of the United States, residing at Hartford, in the county of Hartford and 5 State of Connecticut, have invented certain new and useful Improvements in Work Drivers, of which the following is a specification.

This invention relates to a work driver 10 of the rotary floating chuck type such as shown in my Patent No. 1,187,920 granted June 20th, 1916, and it is the general object of the invention to provide an improved chuck of this character.

15 It is a further object of the invention to provide an improved work driving chuck which will be more compact and rigid than like devices heretofore used, and the exterior contour and appearance of which will be 20 greatly improved.

It is another object of the invention to provide a new and improved type of auxiliary work driving jaw which will grip the work more securely, such type of jaw being 25 adapted for general work driving use.

It is still a further object of the invention to provide means for normally holding the jaw-supporting member in a position 30 central of the chuck or work driver, such means, however, in no way hindering the floating action of the chuck.

With the above and other objects in view as will hereinafter appear, the invention will now be described by reference to the 35 drawing, wherein:

Figure 1 is a longitudinal section of the improved work driver taken on the line 1—1 of Fig. 2.

Fig. 2 is a front elevation of the same, 40 showing a portion of the face plate broken away, one of the work driving jaws removed, and another jaw in section.

Fig. 3 is a cross section taken on line 3—3 of Fig. 1.

45 Fig. 4 is a fragmentary side elevation of the front of the work driver to more clearly illustrate the manner of mounting the work driving jaws.

Fig. 5 is an enlarged diagrammatic side 50 elevation of one of the auxiliary jaw members, the work and portions of the other

cooperating jaw members also being illustrated.

As in my patent above mentioned, I have herein illustrated my invention as applied to the spindle 1 of a lathe, although it will be understood that the invention is in no way limited thereto. The work driver comprising the invention is composed broadly of four elements; namely, the driving member 2, the floating driven member 3, the work driving jaws 4 and the cam ring mechanism 5. The driven member 3 is floatingly mounted on the driving member 2 in such manner as to be driven thereby. 60 I prefer to provide the driven member 3 with a peripheral flange 6 and to notch the flange at one or more places to receive a projection or projections on the driving member. In the drawing I have shown two 65 such projections 7 and a like number of notches in the said flange for receiving such projections. The engagement of these members is sufficiently loose to allow a lateral movement or play of the floating member. 70 In the drawing I have shown two such projections 7 and a like number of notches in the said flange for receiving such projections. The engagement of these members is sufficiently loose to allow a lateral movement or play of the floating member. 75 but the construction is such that the members are in driving contact at all times. The floating driven member 3 is adapted to support the work driving jaws 4 which are preferably radially slidably mounted on the member itself or on means supported thereby. I preferably provide a disk-like member 8 which I secure to the floating member by proper means, such as 80 bolts 9, such member 8 being provided with 85 ways 10 to receive the work driving jaws. This member, which is broadly considered a part of the floating member, with the work driving jaws therein forms the front 90 or face plate of the chuck. The jaws and ways are formed with corresponding guide ribs and grooves 11 whereby the jaws are rigidly held entirely within the outline of the chuck and secured from any lateral movement.

95 Mounted on the driving member 2 and surrounding the driven member 3 is the cam ring mechanism 5. This mechanism comprises base member 12 mounted on the driving member and provided with a cylindrical flange 13 and a cam plate or ring 14 having a like flange 13' mounted on the flange of

the base member and secured by any proper means as by screws 15. This cam ring mechanism is adapted to normally hold the work driving jaws in a closed position, such operation preferably being accomplished by the following mechanism. A spiral spring 16 having one end secured to the cam ring at 17 and the other end secured to the floating driven member 3 at 18 tends to normally rotate the cam ring in the direction indicated by the arrow in Fig. 2. As shown in Figs. 1 and 2, the cam ring has eccentric grooves 19 formed in its front face, each groove being adapted to receive a lug 20 projecting from each jaw. It will be noted that each groove section of the cam ring is notched at one end of the groove to permit the insertion and removal of the jaw with its lug, each notch being closed by a piece 21 secured by a screw or otherwise. It should be obvious from the structure described that the inner end 18 of the spring 16 being held from any appreciable rotation relative to the spindle 1, the outer end 17 of the spring 25 will tend to rotate the cam ring in a jaw-closing direction (indicated by the arrow, Fig. 2) and thereby normally keep the jaws in a closed position.

As heretofore stated, I provide a novel and improved type of work-engaging jaw 22 which while being of particular advantage in a work driver of the present type is in no way limited thereto but is adapted to general use. The peculiar form of the work-engaging portion of this jaw renders it particularly useful in rigidly securing work in place whether such work is to be secured to a work table or to be held rotatably as in the present construction. I have illustrated this jaw in detail in Fig. 5 of the drawing and in Figs. 1 and 2 I have shown the same as applied to a work driver of the type herein disclosed.

Any convenient form of auxiliary work-engaging jaw may be used with my improved chuck but in order to more securely hold and drive the work, I prefer to use the novel auxiliary jaw 22 which I mount in the work-engaging end of each main jaw 4. As shown in Figs. 1, 2 and 5, each jaw 22 comprises a flat plate-like member having a pivot hole 23 and a spiral-like periphery 24 of progressively increasing pitch. I may form such jaw with a work-engaging periphery having stepped spiral portions of progressively increasing pitch or such jaw may be formed with a non-stepped spiral-like periphery gradually and continuously increasing in pitch if desired. This construction will be more clearly understood by reference to Fig. 5 wherein I have illustrated the jaw as having three of the said stepped portions. As shown in Figs. 2 and 5, the work W is initially engaged at the point *a* on each jaw

22, the path *a*—*b* in Fig. 5 preferably being a plain spiral. The continuation of such spiral path is shown in the dot and dash line extending from the point *b* where starts a second spiral peripheral path *b*—*c* steeper in pitch than the path *a*—*b*. The continuation of this path *b*—*c* is shown in the dot and dash line extending from the point *c* where starts a third spiral peripheral path *c*—*d* steeper in pitch than the path *b*—*c*. While I have herein shown the jaw as provided with three stepped portions yet it will be readily understood that any desired number may be formed on each jaw. Each jaw 22 is provided with means for normally holding the lowest work-engaging portion *a* thereof in work-engaging position. Such means herein comprises a plunger 25 seated in the main jaw and normally pressed outward against a projection 26 on the auxiliary jaw by means of a compression spring 27. In operation the jaws initially engage the work as shown in Figs. 2 and 5 with the lowest spiral portion *a* in direct contact with the work. As the chuck is rotated in the direction of the arrow, Fig. 2, the drag of the work on the peripheries of the jaws 22 will rotate such jaws about their pivots 23 in the direction of the arrow in Fig. 5. This action will tightly grip the work within the three jaws and the greater the work-rotating torsion, the tighter will be the grip of the jaws. It should be noted that as each jaw 22 rotates to the left, Fig. 5, in engaging the work, a steeper work-engaging spiral successively comes into contact with the work. In this construction the work is initially engaged at *a* and as the chuck is rotated, a rolling contact between the work and the gradually rising peripheral portion *a*—*b* takes place, thereby tightly wedging the work within the jaws. As soon as the work is wedged tightly within the jaws, it is desirable that the rolling action of the jaws on the work should cease and that the jaws should rotate the work. The path *b*—*c* is steeper in pitch than the path *a*—*b* and therefore the wedging action on the work will be greater at such portion *b*—*c*, such action tending to prevent further rolling contact of the jaws on the work and to rotate the work. The path *c*—*d* is steeper in pitch than the path *b*—*c* and should the work pass over the portion *b*—*c*, it will be engaged by this steeper pitch to stop the rolling contact and to rotate the work.

As stated above, and as shown in my aforesaid patent, the jaw-supporting member 3 is loosely or floatingly mounted on the driving member 2. This construction permits the jaws to adjust themselves to the work even though the latter is not exactly concentric to the center 28 on the spindle 1. When the jaws are not engaged with the work or when

work is being inserted into the chuck, it is desirable that the floating member and jaws be held in a central position in the chuck. I provide means for performing this function, such means being herein illustrated as a plurality of springs 29 secured to an element 30 within the floating member 3 and adapted to surround the center 28 of the spindle. As shown in Fig. 3, the outermost 5 portions of such springs engage the interior of the floating member and normally hold the same in a central position in such manner that work may easily be inserted therein. Also when the chuck is removed 10 from the spindle, the springs 29 keep the element 30 centered in such manner that it may be easily reengaged on the center 28. It should be noted that these springs are not strong enough to interfere with the lateral movement of the floating member 3 whereby the jaws are allowed to adapt 15 themselves to the contour of the work.

Upon the inner side of the base member 12 of the cam ring mechanisms are two projections or lugs 31, and these projections present a convenient means to be engaged by a suitable intermittently operable device for arresting the turning of the cam ring mechanism 5 with the driving member 3, and when this occurs the jaws 4 through the 20 intermediate parts will be opened. There are, of course, other ways in which the motion of the cam ring mechanism with respect to the driven member might be arrested but the said projections in connection with a cooperating member, which I will hereinafter describe, answer satisfactorily in this connection.

Loosely mounted on the forward portion 25 of the spindle 1 is a sleeve 32 provided at its forward end with an annular flange 33. Encircling and slidable on said sleeve is a ring 34 and between said ring and flange 33 is a body 35 of suitable frictional material 30 such as leather, the ring 34, frictional material 35 and flange 33 being pressed together by one or more springs 36, seated in sockets 37 in said ring 34 and bearing against the bottoms of the sockets and also against 45 a disk 38 surrounding the sleeve 32. The disk 38 is provided with one or more guide pins 39 which fit bores in the ring 34 to prevent turning of the said ring as the same is moved back and forth on the sleeve 32. 50 Non-rotatably fitting the said sleeve is a collar 40 and between said collar and disk 38 is a body 41 of frictional material. On the front face of the flange 33 are projections 42 cooperative with the projections 31. 55 The two sets of projections are shown out of contact in Fig. 1 but it will be evident that when the projections 42 are moved into the path of the projections 31 the motion of the cam ring mechanism 5 with the driven mem-

ber 3 will be arrested, when the projections 31 engage the projections 42 to effect the opening of the jaws 4. As a means for shifting the sleeve 32 the lever 43 may be utilized. I have not deemed it necessary to show the mounting of this lever and while it may be either operated by hand or automatically, it will in the case of a lathe be operated automatically. The lever 43 is connected at 44 with the ring 34. It will be apparent that when the lever is swung to the right, Fig. 1, the jaws 4 will be opened through the agency of the intermediate parts while the opposite motion of the said lever will release the jaws so that they can be closed by the power of the spring 16.

It will be evident that I provide in effect two members and interposed friction means between the two and that one of these members turns with respect to the other. The ring 34 and disk 38 constitute together one 80 of said members while the other is composed of the sleeve 32 and the collar 40, the sleeve 32 and collar 40 being turnable with respect to said ring 34 and disk 38. The frictional resistance exerted by the two washers 35 and 41 is greater than the force of the spring 16 so that when the projections 42 arrest the projections 31 in the manner already described, the jaws 4 will be fully opened, but when said jaws have been opened to their 95 maximum extent and when the lugs 20 have encountered the end walls of the cam slots 19, the sleeve 32 and collar 40 will slip on the leather washers 35 and 41 and therefore turn with respect to the ring 34 and 100 disk 38, the jaws 4 remaining open. It will be understood that the instant the projections 42 are moved out of engagement with the projections 31 the jaws 4 will be closed by the spring 16.

What I claim is:

1. A work driver comprising the combination of a driving member, a floating member adapted to be driven by said driving member, an element secured to the floating member and providing a front cover or face plate for the driver, a plurality of work driving jaws rectilinearly slidably mounted in said element, and mechanism for causing the opening and closing of said jaws.

2. A work driver comprising the combination of a driving member, a floating member adapted to be driven by said driving member, a cam plate, an element secured to the floating member and providing a front 110 cover or face plate for the driver, a plurality of work driving jaws slidably mounted in said element and having lugs engaging eccentric grooves in the cam plate, and mechanism for rotating the cam plates to open and 120 close the jaws.

3. A work driver comprising the combination of a driving member, a floating mem-

ber adapted to be driven by said driving member, a cam plate, an element secured to the floating member and providing a front cover or face plate for the driver, a plurality of work driving jaws slidably mounted in said element and having lugs engaging eccentric grooves in the cam plate, a spring for normally rotating the cam plate to close the jaws, and means for causing the opening 10 of said jaws.

4. A work driver comprising the combination of a driving member, a floating member adapted to be driven by said driving member, a plurality of work driving jaws 15 rectilinearly slidably mounted in said floating member, auxiliary jaws pivoted on the work driving jaws and provided with spiral-like work-engaging peripheries, spring means for normally holding the auxiliary 20 jaws with the lowest portions of the peripheries in work-engaging position, and mechanism for causing the opening and closing of said work driving jaws.

5. A work driver comprising the combination of a driving member, a floating member 25 adapted to be driven by said driving member, a plurality of work driving jaws mounted in said floating member, and an auxiliary jaw pivotally mounted on each 30 work driving jaw, each said auxiliary jaw being provided with a spiral-like work-engaging periphery of progressively increasing pitch.

6. A work driver comprising the combination of a driving member, a floating member 35 adapted to be driven by said driving member, work driving jaws mounted on said floating member, and means to normally center said floating member.

40 7. A work driver comprising the combination of a driving member, a floating member adapted to be driven by said driving member, work driving jaws mounted on said floating member, and spring means to normally center said floating member.

8. A work driver comprising the combination of a driving member, a floating member adapted to be driven by said driving member, work driving jaws mounted on said 50 floating member, and a plurality of springs adapted to engage the interior of the floating member to center the same.

9. A work driver comprising the combination of a driving member, a floating member 55 adapted to be driven by said driving member, a plurality of work driving jaws mounted on said floating member, an element within the floating member adapted to engage a carrier spindle, and spring means between 60 the element and floating member for normally keeping such element and floating member in axial alinement.

10. A work driver having work-engaging means comprising a pivoted jaw, said jaw

being provided with a spiral-like work-engaging periphery of progressively increasing pitch.

11. A work driver having work-engaging means comprising a pivoted jaw, said jaw being provided with a periphery comprising 70 work-engaging spiral stepped portions, each successive spiral thereof being of a steeper pitch.

12. A work driver having work-engaging means comprising the combination of 75 a pivoted jaw and spring means engaging the jaw to normally hold the jaw in work-engaging position, said jaw being provided with a spiral-like work-engaging periphery of progressively increasing pitch.

13. A work driver comprising the combination of a rotary chuck having three work-engaging jaws pivotally supported thereby, said jaws each being provided with a spiral-like work-engaging periphery of progres- 85 sively increasing pitch.

14. A work driver comprising the combination of a rotary chuck having three work-engaging jaws pivotally supported thereby, and spring means for normally holding the 90 jaws in work-engaging position, said jaws each being provided with a spiral-like work-engaging periphery of progressively increasing pitch.

15. A work driver comprising the combination of a rotary chuck having three work driving jaws radially slidably mounted therein, and a work-engaging jaw pivotally mounted on each work driving jaw, said work-engaging jaws each being provided 100 with a spiral-like work-engaging periphery of progressively increasing pitch.

16. A work driver comprising the combination of a rotary chuck having three work driving jaws radially slidably mounted 105 therein, a work-engaging jaw pivotally mounted on each work driving jaw, and mechanism for opening and closing the jaws radially while the chuck is rotating, said work-engaging jaws each being provided 110 with a spiral-like work-engaging periphery of progressively increasing pitch.

17. A work driving jaw having a pivot center and a spiral-like work-engaging periphery of progressively increasing pitch.

18. A work driving jaw having a pivot center and a work-engaging periphery comprising spiral stepped portions, each successive spiral thereof being of a steeper pitch.

19. The combination of a work driving jaw having an auxiliary jaw mounted thereon, said auxiliary jaw being provided with a spiral-like work-engaging periphery of progressively increasing pitch.

20. The combination of a work driving 125 jaw having an auxiliary jaw pivotally mounted thereon, said auxiliary jaw being provided with a periphery comprising work-

engaging spiral stepped portions, each successive spiral thereof being of a steeper pitch.

21. The combination of a work driving jaw having an auxiliary jaw pivotally mounted thereon, said auxiliary jaw being provided with a spiral-like work-engaging periphery of progressively increasing pitch,

and spring-pressed means engaging the auxiliary jaw and normally holding the 10 lowest work-engaging portion of its periphery in work-engaging position.

In testimony whereof, I hereto affix my signature.

FRIEDERICH MÜLLER.
